United States Patent Office

Des. 177,445

Patented Apr. 10, 1956

177,445

COMBINATION AUTOMOBILE AND AIRPLANE

Herbert L. Trautmann, San Marino, Calif.

Application February 4, 1955, Serial No. 34,368

Term of patent 14 years

(Cl. D71—1)

Fig. 1.

Fig. 2.

Fig. 5.

Fig. 4.

Figure 1 is a front perspective view of a combination automobile and airplane showing my new design:

Figure 2 is a rear perspective view thereof;

Figure 3 is a top plan view on an enlarged scale; and

Figure 4 is a side elevational view on the same scale as Figure 3.

I claim:

The ornamental design for a combination automobile and airplane, substantially as shown.
